UNITED STATES PATENT OFFICE.

HENRY WESLEY THOMPSON, OF ALTAMONT, ILLINOIS.

FARM GATE.

Application filed May 7, 1927. Serial No. 189,661.

The present invention relates to a farm gate and has for its prime object to provide a gate mounted in a gateway so that said gate may swing horizontally and vertically and may also be slid to a partial open position.

A still further very important object of the invention lies in the provision of a gate structure which is simple, inexpensive to manufacture, strong and durable, thoroughly efficient and reliable in operation, convenient, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of my improved gate structure showing the gate slid to an open position,

Figure 2 is a top plan view thereof showing the gate in an open position,

Figure 3 is an elevation showing the gate closed,

Figure 4 is a detail horizontal section taken substantially on the line 4—4 of Figure 3,

Figure 5 is a detail vertical section showing the hinge connection between the parts of the crane frame,

Figure 6 is an enlarged detail vertical section taken substantially on the line 6—6 of Figure 1.

Referring to the drawing in detail it will be seen that the numeral 5 denotes one post and the numeral 6 the other post which is disposed a suitable distance from the post 5 to form a gateway therebetween. The post 5 has mounted thereon a hinged bracket 7 at its upper end and a hinge bracket 8 at its lower end, said brackets extending toward the post 6. The post 6 is provided with recesses 9 and 10. The post 6 has an aperture 11 leading into the recess 9. The gate comprises a plurality of parallel spaced rails 12, 13, 14, 15 and 16 connected together by vertical cross pieces 17 and 18 at the ends and intermediate cross pieces 19 and 20. A crane frame structure includes a standard 21 having a pin 22 at its upper end rotatable in the bracket 7 and a plate 23 at its lower end having an opening circumjacent an upwardly

disposed extension 8' on the bracket 8. Thus the standard 21 is rotatable between these brackets 7 and 8. A crane arm 25 has one end rounded as at 26 and its edge notched as 27 adjacent said end 26. A recess 28 is formed in the lower portion of the standard 21 to receive the rounded end 26 and a bolt 29 or the like extends through the standard 21 and through an opening 30 in the rounded end 26, the ends of said opening being flared so that the crane arm 28 may be rocked to a limited extent in a vertical plane. A brace rod 32 has a hook end 33 engaged with a plate 34 on the upper end of the standard 21 and the other end of this brace rod 21 projects through an opening 35 in the upper end of the arm 25, the diameter of said opening 35 being greater than the diameter of the rod so that the arm and rod are free to slide. A nut or other abutment 36 is threadedly engaged on the end of the rod 32 and limits the downward movement of the arm 25 so as to relieve the strain on bolt 29. A bracket 38 is mounted on the upper end of the arm 25 and is offset to one side and depends downwardly and has journaled in its lower extremity a roller 39 on which the top rail 12 of the gate rides or rests, said rail 12 being slidable through said bracket 38 as is clearly shown in Figure 6. A bracket 40 is mounted on the side of the standard 21 over the rail 13 and has journaled in its lower end a roller 41 on which the rail 13 rests or rides. A stop hook 42 extends from the side of the standard 21 and depends downwardly over the rail 15 to prevent the upward movement of the gate as a whole on the crane frame. The rails 13 and 15 project beyond the cross member 18 so that they may project into recesses 9 and 10 respectively when the gate is closed. The extremity of the rail 13 is apertured as at 44 to register with aperture 11 so that a pin or the like 45 may pierce these apertures 44 and 11 so as to hold the gate locked in a closed position. This pin 45 is preferably attached to cross member 18 by means of a chain 46.

From the above detailed description it will be seen that the gate may be slid to a partial open position as shown in Figure 1 so that a person can pass through the gateway and so that animals and smaller vehicles may pass therethrough when it is not desired to open the gateway fully. The gate may be swung to a fully open position as is shown in Figure 2, first by sliding the gate to the

dotted line position shown in Figure 2 and then swinging it to the full line position, thus saving steps on the part of the person opening the gate. It will also be seen that 5 the free end of the gate may be tilted upwardly for letting small animals pass thereunder if desired, and more important, for the purpose of lifting the gate over any obstructions which may be in the way of its 10 path when being swung to an open position.

It is thought that the construction, operation, and advantages of this invention will now be quite apparent to those skilled in this 15 art without a more detailed description thereof. It is apparent that the present embodiment of the invention has been disclosed in detail merely by way of example, since in actual practice it attains the features of advantage 20 enumerated as desirable in the statement of the invention and the above description.

It will be further apparent that changes in the details of construction, and in 25 the combination and arrangement of parts may be resorted to without departing from the spirit or scope of the invention as hereinafter claimed or sacrificing any of its advantages.

Having thus described my invention, what 30 I claim as new is:—

1. A gate structure of the class described comprising a pair of posts, a pair of brackets projecting from one post, the other post 35 having a pair of recesses, a standard rotatably mounted between the brackets, an arm, means for limitedly hinging one end of the arm to the lower portion of the standard, a plate at the upper end of the standard, a 40 rod loosely engaged with said plate and projecting through an opening in the other end of the arm, an abutment on the rod to limit the downward movement of the arm, a bracket on said other end of the arm, a roller 45 journalled in said bracket, a bracket on said standard, a roller journalled in said second bracket, a gate comprising a plurality of rails connected by a plurality of cross members, one rail of the gate being slid able 50 through the first bracket and on its roller, another rail of the gate being slid able through the second bracket and on its roller, a stop hook on the standard extending over the top of one of the rails of the gate to 55 loosely hold the lower portion of the gate to the standard and limit the movement thereof.

2. A gate structure of the class described comprising a pair of posts, a pair of brackets

projecting from one post, the other post having a pair of recesses, a standard rotatably mounted between the brackets, an arm, means for limitedly hinging one end of the arm to the lower portion of the standard, a plate at the upper end of the standard, a rod 60 loosely engaged with said plate and projecting through an opening in the other end of the arm, an abutment on the rod to limit the downward movement of the arm, a bracket on said other end of the arm, a roller journalled in said bracket, a bracket on said standard, a roller journalled in said second bracket, a gate comprising a plurality of rails connected by a plurality of cross members, one rail of the gate being slid able 65 through the first bracket and on its roller, another rail of the gate being slid able through the second bracket and on its roller, a stop hook on the standard extending over the top of one of the rails of the gate to 70 loosely hold the lower portion of the gate to the standard and limit the movement thereof.

3. A gate structure of the class described comprising a pair of posts, a pair of brackets projecting from one post, the other post having a pair of recesses, a standard rotatably mounted between the brackets, an arm, means for limitedly hinging one end of the arm to the lower portion of the standard, a plate at the upper end of the standard, a rod 75 loosely engaged with said plate and projecting through an opening in the other end of the arm, an abutment on the rod to limit the downward movement of the arm, a bracket on said other end of the arm, a roller journalled in said bracket, a bracket on said standard, a roller journalled in said second bracket, a gate comprising a plurality of rails connected by a plurality of cross members, one rail of the gate being slid able 80 through the first bracket and on its roller, another rail of the gate being slid able through the second bracket and on its roller, a stop hook on the standard extending over the top of one of the rails of the gate to 85 loosely hold the lower portion of the gate to the standard and limit the movement thereof.

In testimony whereof I affix my signature.

HENRY WESLEY THOMPSON.
